ABSTRACT

The disclosure generally relates to a mattress thermal management system, for example a mattress cooling and/or heating system and in particular incorporating an airflow spacer and/or a suction- and/or discharge-based cooling and/or heating system. Deck-mounted fans beneath a mattress operate in various embodiments to induce a uniform suction flow, a uniform discharge flow, and/or a combined suction/discharge (circulating) flow that enhances the cooling and/or heating rate of the mattress. The mattress thermal management system can be incorporated into a conventional mattress/bed system or into an adjustable bed system. Further, the mattress thermal management system including an airflow spacer can be incorporated into a cover for a conventional mattress foundation or adjustable bed foundation. In another aspect, the disclosure relates to a remote control that controls an adjustable bed and is configured with a children's safety lock feature.

None.

BACKGROUND OF THE DISCLOSURE

Field of the Disclosure

The disclosure generally relates to a mattress thermal management system, in particular incorporating an airflow spacer and/or a suction- and/or discharge-based cooling and/or heating system. Deck-mounted fans beneath a mattress operate in various embodiments to induce a uniform suction flow, a uniform discharge flow, and/or a combined suction/discharge (circulating) flow that enhances the cooling and/or heating rate of the mattress. The mattress thermal management system can be incorporated into a conventional mattress/bed system or into an adjustable bed system. Further, the mattress thermal management system including an airflow spacer can be incorporated into a cover for a conventional mattress foundation or adjustable bed foundation. In another aspect, the disclosure relates to a remote control that controls an adjustable bed and is configured with a children's safety lock feature.

SUMMARY

In an aspect, the disclosure relates to a mattress support structure comprising: a mattress support having a top surface for supporting a mattress and an opposing bottom surface; and an airflow spacer positioned above the top surface of the mattress support, the airflow spacer (i) having a thickness of at least 1 mm or at least 5 mm (e.g., at least 1, 2, 5, 10, 15, or 25 mm and/or up to 5, 7, 10, 15, 25, 50, 75, 100, 150, 250, or 300 mm thick, such as generally measured in a direction normal to the mattress support (top) surface) and (ii) being adapted to permit airflow therethrough; wherein the mattress support structure is free from fans mounted thereto. The airflow spacer can be adapted to permit airflow therethrough based on an open volume in the airflow spacer such as in a three-dimensional fabric. Airflow can be to/from the edge/periphery of the airflow spacer and to/from the external/ambient environment, to/from the top surface of the airflow spacer and to/from the bottom surface of the mattress when present, and/or to/from the bottom surface of the airflow spacer and to/from the mattress support when it includes air flow channels or other open areas permitting air flow therethrough. In various embodiments, the airflow spacer or multiple airflow spacers are the sole or only cooling or

thermal management components to the mattress support structure or corresponding bed/mattress assembly. The mattress support structure or corresponding bed/mattress assembly can be free from other heating and/or cooling elements, whether based on convective and/or conductive heating and/or cooling. It has been found that the presence of the airflow spacer can allow sufficient cooling effect due to conduction and natural convection effects with the ambient environment to the mattress support/bed (e.g., without necessarily including active heating or cooling elements).

In another aspect, the disclosure relates to a mattress support structure comprising: a mattress support having a top surface for supporting a mattress and an opposing bottom surface; a mattress support cover adapted to cover at least the top surface of the mattress support; and an airflow spacer positioned above the top surface of the mattress support, the airflow spacer (i) having a thickness of at least 1 mm or at least 5 mm (e.g., at least 1, 2, 5, 10, 15, or 25 mm and/or up to 10, 15, 25, 50, 75, 100, 150, 250, or 300 mm thick, such as generally measured in a direction normal to the mattress support (top) surface), (ii) being adapted to permit airflow therethrough, and (iii) being an integral component of the mattress support cover. The cover can include elastic bands or other adhesive or attachment means 25 to (removably) attach the cover to the top surface of the mattress support, for example further covering the peripheral edges of the mattress support. In a refinement, the disclosure relates to a mattress assembly system comprising: the mattress support structure including the cover, and a mattress positioned above the mattress support, above the mattress support cover, and above the airflow spacer of the mattress support structure.

Various refinements of the mattress support structure incorporating the airflow spacer are possible.

In a refinement, the airflow spacer is a separate structure from the mattress support.

In another refinement, the airflow spacer is an integral component of the mattress support.

In another refinement, the mattress support structure further comprises a mattress support cover adapted to cover at least the top surface of the mattress support (e.g., including elastic bands or other adhesive or attachment means to removably attach the cover to the top surface of the mattress support, for example further covering the peripheral edges of the mattress support); wherein the airflow spacer is an integral component of the mattress support cover (e.g., generally forming the top surface of the mattress support cover).

In another refinement, the mattress support is a stationary structure.

In another refinement, the mattress support is an adjustable bed comprising at least one moveable mattress support. For example, the mattress support structure can further comprise an electromechanical system adapted to control the at least one moveable mattress support.

In another aspect, the disclosure relates to a mattress assembly system comprising: a mattress support structure according to any of the variously disclosed embodiments or refinements; and a mattress positioned above the mattress support and above the airflow spacer of the mattress support structure. In a refinement, the airflow spacer is a separate structure from the mattress and the mattress support. In another refinement, the airflow spacer is an integral component of the mattress support. In another refinement, the airflow spacer is an integral component of the mattress.

In another aspect, the disclosure relates to a remote control for controlling an adjustable bed and incorporating a

safety lock feature, the remote control comprising: a remote control housing adapted to control an adjustable bed; a first user input control (e.g., first button) on the remote control housing; and a second user input control (e.g., second button) on the remote control housing and spaced apart from the first user input control by a distance of at least 15 mm or at least 25 mm (e.g., at least 15, 20, 25, 35, or 50 mm and/or up to 25, 35, 50, 75, 100, or 150 mm distance between first and second user input controls); wherein: the remote control is configured to be inoperable to send or receive commands from a user in an initial state; and the remote control is configured to become operable to send or receive commands from a user when a predetermined user interaction is performed with the first user input control and the second user input control (e.g., press or otherwise activate both the first and second user input controls in a specified order or simultaneously for a specified amount of time such as at least 1, 2, 3, etc. seconds; corresponds to deactivation of child lock/safety feature, and then all of the user input controls are generally available to receive user commands and send same to the adjustable bed). The handheld housing for the remote control can include a microprocessor, transmitter/receiver/transceiver etc., and user input controls such as a plurality of buttons, and the remote control and housing thereof can be accordingly adapted to send/receive user commands and other information from the remote control to/from the adjustable bed controller. The initial state of the remote is a child-lock or safety state in which the various user input controls of the remote, including the first and second user input controls, are inoperable to receive a user command for bed adjustment in that the default programmed state of the remote control is to ignore user interaction/button pressing with the user input controls. The initial state can be default state of the remote control, for example as a factory default setting or a user selectable setting (e.g., a setting selected by a predetermined interaction with the first and second controls or otherwise).

Various refinements of the remote control incorporating the safety lock are possible.

In a refinement, the remote control, when in an operable state (e.g., in a state where the child lock/safety feature has been deactivated and the remote is operable to receive user commands), is further configured to become inoperable to send or receive commands from a user after a predetermined amount of time. The predetermined amount of time can be a specified timeout time after a period of inactivity with the remote control user controls and/or after the child lock/safety feature has been initially deactivated.

In another refinement, the remote control, when in an operable state (e.g., in a state where the child lock/safety feature has been deactivated and the remote is operable to receive user commands), is further configured to become inoperable to send or receive commands from a user when a predetermined user interaction is performed with the first user input control and the second user input control. The predetermined user interaction to reactivate the child lock/safety feature can be the same or different set of actions with the first and second user input controls that deactivate the child lock/safety feature.

In another refinement, the predetermined user interaction comprises activating the first user input control and the second user input control in a specified predetermined order.

In another refinement, the predetermined user interaction comprises activating the first user input control and the second user input control simultaneously for predetermined time.

In one aspect, the disclosure relates to a mattress support structure (e.g., bed frame) comprising: (a) a mattress support having a top surface for supporting a mattress and an opposing bottom surface (e.g., corresponding to the area beneath the bed/bed frame/mattress support structure); (b) a fan mounted to the mattress support and adapted to transport air (i) from above the top surface of the mattress support to below the bottom surface of the mattress support, (ii) from below the bottom surface of the mattress support to above the top surface of the mattress support, or (iii) both (i) and (ii) (e.g., (i) and (ii) can represent appropriately mounted uni-directional fans, (iii) can represent a bi-directional fan adapted to transport air in either direction); and optionally (c) an electromechanical system adapted to control one or more (e.g., a plurality of) moveable support platforms, wherein the fan is coupled to and controllable by the electromechanical system (e.g., PLC controller mounted to the bed frame or mattress support structure, such as directly to the mattress support or indirectly to the mattress support via lower frame structure; electromechanical system/PLC controller can receive fan operation instructions/commands from a remote control for the adjustable bed). In a refinement, the mattress support comprises an airflow channel between the top surface and the bottom surface to permit airflow therethrough; and the fan is mounted to the mattress support in fluid communication with the airflow channel. In a refinement, the mattress deck is a stationary structure (e.g., a unitary flat member for a fixed mattress support structure or a plurality of flat members collectively defining a flat mattress deck surface for a fixed mattress support structure). In a refinement, the mattress support is an adjustable bed comprising at least one moveable mattress support (e.g., further including an adjustable bed frame to which the mattress support is mounted, such as directly or indirectly). In a refinement, the mattress deck comprises a plurality of support platforms independently moveable relative to each other (e.g., a multi-section mattress deck for an adjustable mattress support structure; each support platform can have at least one fan mounted thereto). In a further refinement, the mattress support structure can comprise a plurality of fans mounted to the mattress support (or support platforms). In one embodiment, the fans are all mounted to the mattress support in a manner adapted to transport air from above the top surface of the mattress support to below the bottom surface of the mattress support (e.g., a mattress-side suction configuration). In another embodiment, the fans are all mounted to the mattress support in a manner adapted to transport air from below the bottom surface of the mattress support to above the top surface of the mattress support (e.g., a mattress-side discharge configuration). In another embodiment, the fans are all mounted to the mattress support in a manner adapted to transport air (i) from above the top surface of the mattress support to below the bottom surface of the mattress support, and (ii) from below the bottom surface of the mattress support to above the top surface of the mattress support. In another embodiment, at least some of the fans are mounted to the mattress support in a manner adapted to transport air from above the top surface of the mattress support to below the bottom surface of the mattress support; and at least some of the fans are mounted to the mattress support in a manner adapted to transport air from below the bottom surface of the mattress support to above the top surface of the mattress support (e.g., a combined mattress-side discharge and mattress-side suction configuration for circulation).

In another aspect, the disclosure relates to a mattress assembly system comprising: (a) the mattress support struc-

ture according to any of the variously disclosed embodiments; (b) a mattress positioned above the mattress support of the mattress support structure; and optionally (c) an airflow spacer positioned intermediate the mattress support structure and the mattress, the airflow spacer adapted to direct airflow (i) to the fans from the mattress, (ii) from the fans to the mattress, or (iii) both (i) and (ii) over substantially the entire area of the mattress. In one refinement, the mattress assembly system further comprises a remote control adapted to transmit fan operational commands to the fan and optionally further adapted to transmit bed repositioning commands to a corresponding adjustable bed frame (e.g., directly to a PLC controller for the fan or a combined PLC controller for the fan and adjustable bed; indirectly to a PLC controller for the fan via a separate PLC controller for the adjustable bed; controller(s) can be mounted on any bed structure, such as the mattress deck or (adjustable) bed frame). In another refinement, the mattress is a conventional mattress. In another refinement, the mattress comprises a mattress containment frame and a plurality of foam cells distributed throughout the containment frame to collectively define a mattress sleep surface. In a further refinement, the mattress further comprises at least one of (a) a plurality of vent holes on a base portion of the mattress containment frame, the vent holes being positioned to permit airflow through the mattress between interstitial areas defined by adjacent foam cells; and (b) a plurality of locator pins on a base portion of the mattress containment frame, wherein each locator pin (i) is adapted to mate with a corresponding open cylindrical channel in a foam cell, and (ii) comprises an open area permitting airflow through the mattress via the open area and the cylindrical channel. In another refinement, the mattress assembly further comprises at least one of a heating unit and a cooling unit mounted to the mattress assembly at a location beneath the mattress support bottom surface, the heating unit and the cooling unit being positioned to direct heated air and cooled air, respectively, to a fan suction side. In another refinement, the airflow spacer is a separate structure from the mattress and the mattress support. In another refinement, the airflow spacer is an integral component of the mattress. In another refinement, the mattress support comprises an airflow channel between the top surface and the bottom surface to permit airflow therethrough; the airflow spacer comprises an airflow channel positioned on a bottom surface of the airflow spacer and in a corresponding location to the airflow channel of the mattress support to permit airflow therethrough; and the fan is mounted to the mattress support in fluid communication with the airflow channel of the mattress support and the corresponding airflow channel of the airflow spacer.

In another aspect, the disclosure relates to a method for cooling or heating a mattress, the method comprising: (a) providing the according to any of the variously disclosed embodiments; (b) operating the fans of the mattress assembly to actively cool or heat the mattress of the mattress assembly (e.g., also cooling or heating the mattress while a user of the bed is sleeping or laying on the mattress). In a refinement, the method comprises operating the fans to actively cool the mattress with ambient environmental air (e.g., operating the fan or fans in a mattress-side suction, discharge, or recirculation flow). In another refinement, the method comprises operating the fans to actively cool the mattress with actively cooled air (e.g., operating the fan or fans in a mattress-side suction, discharge, or recirculation flow; using an integrated cooling unit with the mattress assembly beneath the mattress support; using a remote cooling unit adapted to direct cooled air relative to ambient

beneath the mattress support). In another refinement, the method comprises operating the fans to actively heat the mattress with actively heated air (e.g., operating the fan or fans in a mattress-side suction, discharge, or recirculation flow; using an integrated heating unit with the mattress assembly beneath the mattress support; using a remote heating unit adapted to direct heated air relative to ambient beneath the mattress support).

10 In another aspect, the disclosure relates to a mattress assembly system comprising: (a) a mattress support structure; (b) a mattress positioned above the mattress support of the mattress support structure; and (c) an airflow spacer with a minimum thickness of 1 mm or 5 mm positioned intermediate the mattress support structure and the mattress, the airflow spacer adapted to permit airflow therethrough.

15 In another aspect, the disclosure relates to a mattress assembly system comprising: (a) a mattress support structure incorporating an airflow spacer, the airflow spacer having a minimum thickness of 1 mm or 5 mm and adapted to permit airflow therethrough and (b) a mattress positioned above the mattress support of the mattress support structure.

20 In another aspect, the disclosure relates to a cover for a mattress support structure (e.g., bed frame) having a top surface and an opposing bottom surface. In a refinement, the cover for a mattress support comprises an airflow spacer with a minimum thickness of 1 mm or 5 mm between the top surface and the bottom surface, the airflow spacer adapted to permit airflow therethrough.

25 30 Additional features of the disclosure may become apparent to those skilled in the art from a review of the following detailed description, taken in conjunction with the drawings, examples, and appended claims.

BRIEF DESCRIPTION OF THE DRAWINGS

35 For a more complete understanding of the disclosure, reference should be made to the following detailed description and accompanying drawings wherein:

40 FIG. 1 is a side exploded view of a mattress thermal management system according to the disclosure.

FIG. 1A is a side exploded view of a mattress thermal management system incorporating an airflow spacer according to the disclosure.

45 FIG. 1B is a side exploded view of a mattress thermal management system incorporating an airflow spacer as a component of a mattress support cover according to the disclosure.

FIG. 2 is a top perspective illustration of a mattress and airflow spacer according to the disclosure.

50 FIGS. 3a and 3b illustrate bottom views of a mattress deck and an associated adjustable bed frame according to the disclosure (3a: twin deck and bed frame; 3b: queen deck and bed frame).

55 FIGS. 4a and 4b are schematics of the bottom side of the mattress deck of FIG. 3b showing possible placements of cooling fans.

FIG. 5 is a side view of mattress thermal management system embodiments according to the disclosure (A: mattress-side airflow discharge; B: mattress-side airflow suction; C: mattress-side airflow combined discharge and suction).

60 FIG. 6 is a top perspective illustration of a mattress containment frame according to the disclosure.

FIG. 7 is a side cut-away view of the mattress containment frame of FIG. 6 and a corresponding airflow spacer according to the disclosure.

FIG. 8 top view of a remote control for an adjustable bed and configured with a child safety lock feature.

While the disclosed apparatus and methods and are susceptible of embodiments in various forms, specific embodiments of the disclosure are illustrated (and will hereafter be described) with the understanding that the disclosure is intended to be illustrative, and is not intended to limit the claims to the specific embodiments described and illustrated herein.

DETAILED DESCRIPTION

The disclosure generally relates to a mattress thermal management system, for example a mattress cooling system and in particular a suction-based cooling system. In other embodiments, the mattress thermal management system can operate as a mattress heating system. Deck-mounted fans beneath a mattress operate in various embodiments to induce a uniform suction flow or a combined suction/discharge (circulating) flow that enhances the cooling or heating rate of the mattress. Suitably, air is used as the fluid heat transfer medium, whether the system is operating for mattress cooling or heating. In other embodiments, a gaseous fluid other than air may be used as a fluid heat transfer medium circulated by the deck-mounted fans (e.g., alone or in combination with air). Accordingly, references in the following description to "air" and "airflow" apply as well to various other gaseous heat transfer fluids more generally. The mattress cooling system can be incorporated into a conventional mattress/bed system or into an adjustable bed system. In other embodiments, the mattress cooling system can be comprised solely of an airflow spacer with a minimum thickness of 1 mm or 5 mm positioned intermediate a mattress support structure and a mattress, the airflow spacer adapted to permit significant airflow therethrough. In other embodiments, the mattress cooling system can be comprised of a mattress support structure incorporating an airflow spacer with a minimum thickness of 1 mm or 5 mm, the airflow spacer adapted to permit significant airflow therethrough and a mattress positioned above the mattress support of the mattress support structure. In other embodiments, the mattress cooling system can be comprised of a cover for a mattress support structure having a top surface and an opposing bottom surface and incorporating an airflow spacer with a minimum thickness of 1 mm or 5 mm between the top surface and the bottom surface, the airflow spacer adapted to permit significant airflow therethrough.

FIG. 1 is a side exploded view of a mattress thermal management (e.g., cooling and/or heating) system 10 according to the disclosure. The illustrated mattress thermal management system 10 includes a mattress deck (or mattress support) 100, optionally an airflow spacer 200 positioned thereon, and a mattress 300 positioned above the mattress deck 100 (e.g., sitting upon the airflow spacer 200 when present or sitting directly on the mattress deck 100). FIG. 2 is a top perspective illustration of the mattress 300 according to a particular embodiment of the disclosure. More generally, the mattress thermal management system 10 and components thereof can be used with a fixed-frame bed or an adjustable-frame bed.

The mattress deck 100 includes a deck support platform 110, for example including a plurality of deck support platforms 110A-110D as illustrated. A single unitary deck support platform 110 is suitable for a conventional (non-adjustable) bed assembly. A deck support platform 110 formed from a plurality of deck support platforms 110A-110D is suitable for an adjustable bed assembly. In some

embodiments the support platform(s) 110 can be formed from a rigid support material such as wood or metal. In other embodiments the support platform(s) can be formed from a flexible fabric or material. The deck support platform 110 includes a fan 120 (e.g., axial fan, centrifugal fan, cross-flow fan, or other means for blowing or otherwise transporting air or gaseous fluid) mounted thereto, for example plurality of fans 120A-120D as illustrated. While each deck support platform 110A-110D is illustrated as having a corresponding fan 120A-120D, each platform 110A-110D can have none, one, or more than one corresponding fans 120 mounted thereto. Each fan 120 is mounted to the deck 110 adjacent to, within, or otherwise in fluid communication with a corresponding airflow channel 130, thereby permitting airflow through the mattress 300, the airflow spacer 200 (when present), and the mattress deck (i.e., via the airflow channel 130 and the fan 120) in either direction.

Each fan 120 has a suction side 122 (i.e., a fan surface/plane across which air is drawn from the external environment into the fan interior) and a discharge side 124 (i.e., a fan surface/plane across which air is expelled from the fan interior to the external environment). As illustrated, the fan 120 can be mounted on its suction side 122 to the deck support platform 110, thereby creating a suction air flow during fan operation, drawing air through the mattress 300 and expelling the air beneath the deck support platform 110 to the external environment underneath the bed. As alternatively illustrated, the fan 120 can be mounted on its discharge side 124 to the deck support platform 110, thereby creating a discharge air flow during fan operation, drawing air from the external environment underneath the bed, through the deck support platform 110 and then through the mattress 300. In some embodiments, the fans 120A-120D are all mounted in the same suction/discharge orientation (e.g., all mounted on their suction sides 122 to the platform 110; all mounted on their discharge sides 124 to the platform 110). In other embodiments, the fans 120A-120D are mounted in a mixed suction/discharge orientation (e.g., some mounted on their suction sides 122 to the platform 110 and some mounted on their discharge sides 124 to the platform 110). In some embodiments, some or all of the fans 120A-120D are unidirectional fans (i.e., having fixed suction and discharge sides, being intended to transport air in a single direction). In some embodiments, some or all of the fans 120A-120D are bidirectional fans (i.e., having variable suction and discharge sides depending on impeller rotation, being capable of transporting air in two different (opposing) directions).

The airflow spacer 200 can be any type of structure that includes an open void volume permitting airflow therethrough and directing the airflow to improve the spatial distribution (e.g., uniformity thereof) of airflow through the mattress 300 (e.g., in particular when the fans 120A-120D are positioned at discrete, non-uniformly spaced locations in the deck support platform 110). Suitably, the airflow spacer 200 is formed from a flexible material to accommodate a moveable deck support platform 110 of an adjustable bed. Suitable structure for the airflow spacer 200 includes a mesh fabric (e.g., three-dimensional fabric) or other porous material, a manifold structure, a duct structure, a channel structure, and a cavity structure. In some embodiments, the airflow spacer 200 is a separate structure from the mattress 300 and the mattress deck 100. In other embodiments, the airflow spacer 200 can be an integral component of the mattress deck 100 (e.g., with the platform(s) 110 thereof) or it can be an integral component of the mattress 300 (e.g., with the base 310 thereof).

The mattress **300** is not particularly limited, and it can be a conventional mattress **300** (e.g., a spring or coil mattress, memory foam mattress, air mattress) with a base **310** (e.g., a continuous fabric material) suitable for use on a mattress support structure such as a fixed bed frame or an adjustable bed frame. In the illustrated embodiment, the mattress **300** includes a mattress containment frame **305** including a plurality of foam cells (or foam springs) **340** positioned in the frame **305** to provide the sleeping support surface for the mattress. The mattress containment frame **305** includes a lower/bottom base **310**, sidewalls **320**, and endwalls **330** which generally define the interior frame **305** volume housing the foam cells **340**. The sidewalls **320** and endwalls **330** suitably are formed from a foam material. The base **310** can be a generally continuous fabric material (e.g., a continuous surface but sufficiently thin and porous at a small scale to permit airflow therethrough between the mattress **300** and the airflow spacer **200**, such as a fabric material). In some embodiments, the base **310** can include one or more larger open areas (e.g., airflow channels) to enhance the rate of airflow therethrough between the mattress **300** and the airflow spacer **200**. The mattress **300** and optionally the airflow spacer **200** (e.g., as a separate or integral component of the mattress **300**) are generally positioned above the mattress support **100**, for example sitting directly atop the deck support sections **110A-110D**.

FIGS. **3a** and **3b** illustrate a bottom view of a mattress deck **100** and an associated adjustable bed frame **400** according to the disclosure (**3a**: twin deck and bed frame; **3b**: queen deck and bed frame). The adjustable frame **400** generally provides the mechanical, electrical, and electronic support and articulation components for the mattress system **10** and mattress deck **100**. As illustrated, the adjustable frame **400** includes a frame support **410**. Each deck support section **110A-110D** can be fixedly or removably mounted (e.g., via bolts, screws, or other fastener or adhesive components) to the underlying frame support **410** such that when one or more sections of the frame support section **410** are articulated, the deck support sections **110A-110D** are correspondingly articulated. As illustrated, the adjustable frame **400** further includes a subframe **430**, for example a rigid, non-articulatable frame structure which sits on a floor or within a decorative bed frame common in the furniture industry such as a platform bed (e.g., via various leg elements, not shown) and provides stability for the mattress system **10** as the adjustable frame **400** is articulated to various different positions. The adjustable frame **400** can further include one or more support members **420** connecting structure between the subframe **430** and the frame support **410**. As further illustrated, the adjustable frame **400** can include one or more actuators **440** variously mounted to one or more of the subframe **430**, a support member **420**, and the frame support **410**. In some embodiments, the subframe **430**, the support members **420**, and the frame support **410** can be formed from metal such as steel. The actuators **440** can be any of those commonly known in the art. The actuators **440** and, correspondingly, the configuration or position of the adjustable frame **400**, mattress support **100**, and mattress **300** can be controlled and adjusted by a suitable power supply **450**, adjustable bed controller **450** (e.g., programmable logic controller or otherwise, which may be integrated with the power supply or separate structure), and a remote control **460** to deliver repositioning commands and/or thermal management system commands (e.g., fans/system on or off; fans/system in heating or cooling mode; fan/system intensity/speed). In some embodiments, a programmable timer may be incorporated into the adjustable

bed controller **450**, the remote control **460**, or otherwise, thus allowing the fans **120** to be programmably operated in any desired heating and/or cooling mode at a user-specified fan intensity/speed, temperature set point, start time, a user-specified duration, and/or a user-specified end time.

In some embodiments, the controller **450** is a combined controller providing power and send/receive command/control functionality to both the adjustable bed frame **400** (e.g., repositioning commands, power to actuators **440**, etc.) and the thermal management system **10** (e.g., thermal management commands, power to fans **120**, etc.). In other embodiments, the controller **450** can include two separate controller structures: a first controller providing power and send/receive command/control functionality to the adjustable bed frame **400** and a second controller providing power and send/receive command/control functionality to the thermal management system **10**. In such embodiments, the first and second controllers can be electronically connected (e.g., wired or wireless connection), for example in a master-slave arrangement. For example, the first controller can be a master controller capable of receiving commands from the remote **460** for both the adjustable bed frame **400** and the thermal management system **10**, and then the first controller can pass commands for the thermal management system **10** to the second controller for execution. In other embodiments, each of the first and second controllers may be configured to independently receive and execute commands from the remote **460**.

The remote control **460** is not particularly limited. In an embodiment, the remote **460** includes a touch screen **462** to receive user commands (e.g., regarding adjustable bed position, fan operation, heating/cooling modes, timing of same, etc.) and/or to display to the user the current status of the adjustable bed position and/or the thermal management system (e.g., reflecting confirmation of successfully executed commands as sensed and reported by the controller **450**). In some embodiments, the remote **460** can be a wired unit connected to the controller **450**, for example a dedicated remote **460** for the adjustable bed. In other embodiments, the remote **460** can include a wireless transceiver for communication (e.g., two-way communication) with a corresponding transceiver in the controller **450**. Any suitable wireless communication protocol may be used to send commands from the remote **460** to the controller **450** (e.g., and optionally to receive feedback from the **450** confirming successful execution of the sent commands), for example including infrared (IR) and/or radio frequency (RF) (e.g., WIFI, BLUETOOTH, or otherwise) wireless protocols. In some embodiments, the wireless remote **460** can be communication matched with the controller **450**, for example using a communication key or code key transmitted and received between the remote **460** and controller **450** to confirm that the controller **450** may receive and execute user commands from the remote **460** (e.g., further including a confirmation from the controller **450** to the remote **460** that the communication key or code key has been received and accepted). The wireless remote **460** can be a dedicated remote **460** for the adjustable bed. In other embodiments, the wireless remote **460** can be a mobile electronic device (e.g., cell phone, smart phone, tablet computer) running a software application providing a user interface for control of adjustable bed functions and/or thermal management system functions. The remote **460** also can implement various memory functions associated with the adjustable bed and/or thermal management system, for example using memory-stored settings related to the same in one or more of the remote **460**, the controller **450**, and a location separate from the remote

11

460 and the controller 450 (e.g., at a remote network location). Memory settings related to adjustable bed position, thermal management settings (e.g., fan speed, duration, start/stop time, temperature set point), or both can be stored in memory (e.g., based on a user indication to save one or more settings as presets for later recall) using the remote 460, and the memory settings can be recalled at a later time by the remote 460 as command for execution by the controller 450. In some embodiments, the memory setting can relate to a single setting (e.g., an adjustable bed position, a thermal management setting). In other embodiments, the memory setting can represent a global command relating to multiple settings (e.g., one or more adjustable bed positions for multiple bed segments, one or more thermal management settings, combinations thereof, etc.).

The thermal mattress system 10 can further include one or more temperature sensors 160 (e.g., a thermocouple or other suitable conventional means for sensing temperature). The sensor(s) 160 can be located at any desired location(s) in the mattress system, for example on the mattress deck 100, the airflow spacer 200, the mattress 300, and/or the adjustable bed frame 400. For example, the sensor(s) can be located on a fan 120 surface (e.g., as illustrated; such as on or near an intake or exhaust surface), a deck support 110 surface (e.g., bottom or top side thereof), an interior or exterior surface of the airflow spacer 200, an interior or exterior surface of the mattress 300 or a component thereof (e.g., base 310, sidewall 320, endwall 330, foam cylinder 340, top or bottom surface of mattress 300 as a whole). The temperature sensor(s) 160 can be coupled to the controller 450 (e.g., a component thereof for the thermal management system 10) for form a temperature feedback control loop for the thermal management system 10. Given a temperature set point (e.g., preset or selected by a user), the controller 450 can be programmed to monitor current temperature and adjust the thermal management system 10 settings based on the set point (e.g., increase or decrease heating or cooling such as by adjusting fan intensity/speed, fan operation duration, heating/cooling unit output temperature). In some embodiments, a user can enter a desired set point in terms of a user-sensible temperature (e.g., mattress upper surface temperature, ambient temperature above the mattress upper surface), and the controller 450 feedback control logic can be programmed to use the temperature actually sensed at a different location by the sensor 160 as a proxy for the set point (e.g., by specifying or determining a relationship between the desired set point and the sensed temperature).

As shown, the fans 120 may be irregularly spaced/positioned on the underside of the mattress deck 100 to accommodate other mechanical and/or electronic bed components, in particular for the adjustable bed frame 200. The fans 120 can be powered and controlled by the electromechanical system of the adjustable bed (e.g., illustrated via the wires from fans to the power supply/programmable logic controller 450 (PLC), which can provide power to the fans 120 and can provide operating instructions to the fans 120, for example as received from an external remote control unit 460 for the adjustable bed). FIG. 4a is a schematic of the bottom side of the mattress deck 100 of FIG. 3b showing the placement of four cooling fans 120 as well as optional placement locations 120' for additional fans (e.g., if greater airflow is desired). FIG. 4b is a schematic of the bottom side of the mattress deck 100 in alternative embodiment including one fan 120 in the head section 110A and one fan 120 in the foot section 110B of the mattress deck 100.

FIG. 5 is a side view of mattress cooling system embodiments according to the disclosure (A: mattress-side airflow

12

discharge; B: mattress-side airflow suction; C: mattress-side airflow combined discharge and suction). In FIG. 5A, both fans 120 are mounted (or otherwise operating in) a mattress-side discharge orientation in which airflow is transported from beneath the deck support platform 110 and up through the mattress 300. In FIG. 5B, both fans 120 are mounted (or otherwise operating in) a mattress-side suction orientation in which airflow is transported from above the mattress 300, through the mattress 300 and the deck support platform 110, and to the area beneath the deck support platform 110. In FIG. 5C, the fans 120 are alternatively mounted (or otherwise operating in) in a mattress-side suction orientation and a mattress-side discharge orientation, thereby creating a recirculating airflow pattern for enhanced cooling effectiveness. In any of the various fan 120 configurations and operating modes (e.g., mattress-side suction, discharge, or recirculation flow), the operation of the fans and be used to actively cool the mattress 300 with ambient environmental air, for example from either above the mattress 300, below the mattress deck 100, or both.

Other cooling embodiments for cooling the mattress 300 of the mattress system 10 are possible. For example, in the embodiments illustrated in FIGS. 5A and 5C, a cooler or cooling unit 150 may be positioned below the mattress deck 100 (e.g., mounted thereto and/or to mattress support structure therebelow such as the adjustable bed frame 400 or a component thereof), and the cooler 150 can be positioned to cool air 152 being fed upwards into the mattress 300 (e.g., by either fan 120 illustrated in FIG. 5A; by the left-illustrated fan 120 in FIG. 5C), thus actively cooling the mattress 300. In an embodiment, the cooler 150 can be a portable cooling or air conditioning unit 150 capable of cooled air relative to the ambient environment. Alternatively, the cooler 150 may be positioned remotely from the mattress deck 100 (or bed more generally) and the cooler 150 can direct cold air 152 from the remote location to the fans 120 for circulation through the mattress 300. The remote cooler 150 can be a portable cooling or air conditioning unit 150 spaced proximately to direct cold air 152 below the mattress deck 100 to be fed upwards into the mattress 300. In some embodiments, the remote cooler 150 can be an HVAC (heating, ventilation, air conditioning) system or a component thereof, such as a home HVAC system configured to direct cold air 152 below the mattress deck 100 to be fed upwards into the mattress 300. In embodiments including a cooler 150, the mattress system 10 may be independently operated at the discretion of the user in a cooling mode using ambient environmental air (e.g., as described above without the cooler 150 being active) or a cooling mode using the cold air 152 from the cooler 150 to cool the mattress 300.

In some embodiments, the mattress system 10 can be adapted to heating the mattress 300 instead of cooling. For example, in the embodiments illustrated in FIGS. 5A and 5C, a heater or heating unit 140 may be positioned below the mattress deck 100 (e.g., mounted thereto and/or to mattress support structure therebelow such as the adjustable bed frame 400 or a component thereof), and the heater 140 can be positioned to heat air 142 being fed upwards into the mattress 300 (e.g., by either fan 120 illustrated in FIG. 5A; by the left-illustrated fan 120 in FIG. 5C), thus actively heating the mattress 300. In an embodiment, the heater 140 can be a portable heating unit 140 such as an electrically powered semiconductor-based micro thermal module capable of providing radiant heat relative to the ambient environment. Alternatively, the heater 140 may be positioned remotely from the mattress deck 100 (or bed more

generally) and the heater 140 can direct hot air 142 from the remote location to the fans 120 for circulation through the mattress 300. The remote heater 140 can be a portable heating unit 140 spaced proximately to direct hot air 142 below the mattress deck 100 to be fed upwards into the mattress 300. In some embodiments, the remote heater 140 can be an HVAC system or a component thereof (e.g., where the same HVAC system is capable of providing cool air for cooling as above or hot air for heating), such as a home HVAC system configured to direct hot air 142 below the mattress deck 100 to be fed upwards into the mattress 300. In embodiments including a heater 140, the mattress system 10 may be independently operated at the discretion of the user in either a cooling mode (e.g., as described above without the heater 140 being active) or in a heating mode (e.g., with the heater 140 actively supplying heat to the airflow entering the mattress 300).

FIG. 6 is a top perspective illustration of a mattress containment frame 305 according to the disclosure, and FIG. 7 is a side cut-away view of the mattress containment frame 305 and a corresponding airflow spacer 200 according to the disclosure. In an embodiment, the base 310 of the frame 305 can include a plurality of locator recesses 312 that are size and shaped (e.g., cylindrical as shown) to accommodate and seat corresponding foam cells 340. Each locator recess 312 includes a locator pin (or protrusion) 314 that mates with the corresponding open cylindrical channel 342 of a foam cell 340. The locator pin 314 has an open top area 318 to permit airflow through the open cylindrical channel of the foam cell 340, through the open top area of the locator pin 314, and then into the airflow spacer 200. As further illustrated, the base 310 includes a plurality of vent holes 316 positioned to permit airflow through the interstitial areas between adjacent foam cells 340 and the airflow spacer 200. The locator pin 314 open areas and vent holes 316 permit air circulation within the mattress 300, thereby enhancing the cooling effect of the fans 120. In the illustrated embodiment of FIG. 7, the airflow spacer 200 has an open channel-type structure and it further includes an open airflow channel area (or hole) 230 that generally corresponds to a similarly positioned airflow channel 130 in the deck support platform 110. In other mattress embodiments, airflow channels/structures through the thickness of the mattress 300 can be incorporated into a conventional mattress 300 as desired, thereby providing an airflow path for cooling and/or heating airflow paths between the top and bottom of the mattress 300 (e.g., similar to those provided by the vent holes 316 and open areas 318 in the illustrated embodiment), for example also in fluid communication with the open airflow channel area (or hole) 230 (e.g., in the bottom of the airflow spacer 200) and the airflow channel 130 in the mattress deck support 110.

FIGS. 1A and 1B illustrate further embodiments of the mattress thermal management system 10 according to the disclosure which include the airflow spacer 200, and which can either include or omit the deck-mounted fans 120 described herein.

In another embodiment, the mattress thermal management system 10 comprises of a mattress support structure 100 (e.g., bed frame) incorporating an airflow spacer 200, the airflow spacer 200 having a minimum thickness T of 1 mm or 5 mm and adapted to permit airflow therethrough, and a mattress 300 positioned above the mattress support of the mattress support structure 100. In a refinement, the airflow spacer 200 can be any type of structure that includes an open void volume permitting significant airflow therethrough and permitting the improvement of the spatial distribution (e.g., uniformity thereof) of airflow. Suitably, the airflow spacer

200 is a formed from a flexible material to accommodate a moveable deck support platform of an adjustable bed. Suitable structure includes a mesh fabric (e.g., three-dimensional fabric) or other porous material, a manifold structure, a duct structure, a channel structure, and a cavity structure.

In another embodiment, the mattress thermal management system 10 comprises of a mattress support structure 100 (e.g., bed frame) incorporating an airflow spacer 200, the airflow spacer 200 having a minimum thickness T of 1 mm or 5 mm and adapted to permit airflow therethrough. In a refinement, the airflow spacer 200 can be any type of structure that includes an open void volume permitting significant airflow therethrough and permitting the improvement of the spatial distribution (e.g., uniformity thereof) of airflow. Suitably, the airflow spacer 200 is a formed from a flexible material to accommodate a moveable deck support platform of an adjustable bed. Suitable structure includes a mesh fabric (e.g., three-dimensional fabric) or other porous material, a manifold structure, a duct structure, a channel structure, and a cavity structure.

In another embodiment, the mattress thermal management system 10 comprises of a mattress support structure 100 (e.g., bed frame), a mattress 300 positioned above the mattress support of the mattress support structure 100 and an airflow spacer 200 with a minimum thickness T of 1 mm or 5 mm positioned intermediate the mattress support structure 100 and the mattress 30, the airflow spacer 200 adapted to permit airflow therethrough. In a refinement, the airflow spacer 200 can be any type of structure that includes an open void volume permitting significant airflow therethrough and permitting the improvement of the spatial distribution (e.g., uniformity thereof) of airflow. Suitably, the airflow spacer 200 is a formed from a flexible material to accommodate a moveable deck support platform of an adjustable bed. Suitable structure includes a mesh fabric (e.g., three-dimensional fabric) or other porous material, a manifold structure, a duct structure, a channel structure, and a cavity structure.

In another embodiment, the mattress thermal management system 10 comprises of a cover 210 for a mattress support structure 100 (e.g., bed frame) with the cover 210 having a top surface 210A and an opposing bottom surface 210B. In a refinement, the cover 210 for a mattress support comprises an airflow spacer 200 with a minimum thickness of 1 mm or 5 mm that can be any type of structure that includes an open void volume permitting significant airflow therethrough and permitting the improvement of the spatial distribution (e.g., uniformity thereof) of airflow. Suitably, the cover 210 and/or airflow spacer 200 is a formed from a flexible material to accommodate a moveable deck support platform of an adjustable bed. Suitable structure includes a mesh fabric (e.g., three-dimensional fabric) or other porous material, a manifold structure, a duct structure, a channel structure, and a cavity structure. In some embodiments, the cover 210 is designed to cover only the top surface of a mattress support structure 100. In other embodiments, the cover is designed to cover the entire mattress support structure 100.

In another aspect, the disclosure relates to a remote control that controls an adjustable bed and is configured with a children's safety lock feature, for example as illustrated in FIG. 8.

Adjustable beds are able to articulate in many different fashions and angles. As a result, the possibility exists that if an unsupervised child accidentally activates the adjustable bed using the bed's remote control, the child may suffer an injury from the resulting articulation of the bed. Therefore, the need exists for an adjustable bed's remote control to include a children's safety lock feature that makes the

remote inoperable unless a specific action that is defined by the remote control is taken in order to deactivate the safety lock feature, unlocking the remote and making it operable. However, implementing such a feature on a device with a small footprint such as remote control is difficult and such features can be prone to accidental deactivation. Therefore, the need exists to design a remote control with an innovative safety lock feature that is difficult for a child to deactivate.

In one embodiment of the disclosure, a remote control **460** for an adjustable bed is designed such that two or more buttons **464A**, **464B** of the remote control's general set of buttons **464** are configured such that they are minimally spaced by a distance D of at least one inch or one and one half centimeters (e.g., at least about 25 mm or at least about 15 mm) from each other. The remote control **460** is designed such that it incorporates a children's safety lock feature that makes the remote **460** inoperable unless a certain action that is defined by the remote control's software is performed. Such action is defined by the remote control's software as pressing at the same time two or more of the buttons **464A**, **464B** that are minimally spaced by at least one inch or one and one half centimeters (e.g., at least about 25 mm or at least about 15 mm) from each other. After the remote control **460** is unlocked, the remote **460** will once again become inoperable after a specific time period of inactivity, as defined in the remote control's software or by once again pressing at the same time the two or more buttons **464A**, **464B** that are minimally spaced by at least one inch or one and one half centimeters (e.g., at least about 25 mm or at least about 15 mm) from each other.

In another embodiment of the disclosure, a remote control **460** for an adjustable bed is designed such that two or more buttons **464A**, **464B** of the remote control's general set of buttons **464** are configured such that they are minimally spaced by a distance D of at least one inch or one and one half centimeters (e.g., at least about 25 mm or at least about 15 mm) from each other. The remote control **460** is designed such that it incorporates a children's safety lock feature that makes the remote inoperable unless a certain action that is defined by the remote control's software is performed and such action is defined by the remote control's software as pressing at the same time two specific buttons **464A**, **464B** that are minimally spaced by at least one inch or one and one half centimeters (e.g., at least about 25 mm or at least about 15 mm) from each other. After the remote control **460** is unlocked, the remote will once again become inoperable after a specific time period of inactivity, as defined in the remote control's software or by once again pressing at the same time the two specific buttons **464A**, **464B** that are minimally spaced by at least one inch or one and one half centimeters (e.g., at least about 25 mm or at least about 15 mm) from each other.

In another embodiment of the disclosure, a remote control **460** for an adjustable bed is designed such that two or more buttons **464A**, **464B** of the remote control's general set of buttons **464** are configured such that they are minimally spaced by a distance D of at least one inch or one and one half centimeters (e.g., at least about 25 mm or at least about 15 mm) from each other. The remote control **460** is designed such that it incorporates a children's safety lock feature that makes the remote **460** inoperable unless a certain action that is defined by the remote control's software is performed and such action is defined by the remote control's software as pressing at the same time two specific buttons **464A**, **464B** that are minimally spaced by at least one inch or one and one half centimeters (e.g., at least about 25 mm or at least about 15 mm) from each other and pressing the buttons **464A**,

464B for at least a specific period of time that is defined by the remote control's software. After the remote control **460** is unlocked, the remote **460** will once again become inoperable after a specific time period of inactivity, as defined in the remote control's software or by once again pressing at the same time the two specific buttons **464A**, **464B** that are minimally spaced by at least one inch or one and one half centimeters (e.g., at least about 25 mm or at least about 15 mm) from each other and pressing the buttons for at least the specific period of time that is defined by the remote control's software.

In another embodiment of the disclosure, a remote control **460** for an adjustable bed is designed such that two or more buttons **464A**, **464B** of the remote control's general set of buttons **464** are configured such that they are minimally spaced by a distance D of at least one inch or one and one half centimeters (e.g., at least about 25 mm or at least about 15 mm) from each other. The remote control **460** is designed such that it incorporates a children's safety lock feature that makes the remote **460** inoperable unless a certain action that is defined by the remote control's software is performed and such action is defined by the remote control's software as pressing at the same time two specific buttons that are minimally spaced by at least one inch or one and one half centimeters (e.g., at least about 25 mm or at least about 15 mm) from each other and pressing the buttons **464A**, **464B** for at least three seconds. After the remote control **460** is unlocked, the remote **460** will once again become inoperable after a specific time period of inactivity, as defined in the remote control's software or by once again pressing at the same time the two specific buttons **464A**, **464B** that are minimally spaced by at least one inch or one and one half centimeters (e.g., at least about 25 mm or at least about 15 mm) from each other and pressing the buttons for at least three seconds.

In another embodiment of the disclosure, a remote control **460** for an adjustable bed is designed such that two or more buttons **464A**, **464B** of the remote control's general set of buttons **464** are configured such that they are minimally spaced by a distance D of at least one inch or one and one half centimeters (e.g., at least about 25 mm or at least about 15 mm) from each other. The remote control **460** is designed such that it incorporates a children's safety lock feature that makes the remote **460** inoperable unless a certain action that is defined by the remote control's software is performed and such action is defined by the remote control's software as pressing a specific sequence of the remote control's buttons **464A**, **464B**, with the specific sequence of buttons **464A**, **464B** chosen by the remote control's user and programmed into the remote control's software. After the remote control **460** is unlocked, the remote **460** will once again become inoperable after a specific time period of inactivity, as defined in the remote control's software or by once again pressing the specific sequence defined by the remote control's software.

Rawls-Meehan U.S. Pat. Nos. 7,321,811, 7,465,280, 7,805,785, 7,930,783, 7,933,669, 7,979,169, 8,019,486, 8,032,263, 8,032,960, 8,046,114, 8,046,115, 8,046,116, 8,046,117, 8,050,805, 8,069,512, 8,078,336, 8,078,337, 8,150,562, 8,375,488, 8,565,934, 8,682,457, and 9,474,384 are incorporated herein by reference in their entireties and variously disclose mattresses including foam springs or foam cells and materials/configurations therefor, adjustable bed assemblies including adjustable mattress frames, electrical, mechanical, and electronic components associated therewith, and remote controls for use therewith, all of

17

which may be used individually or collectively in combination with the mattress cooling system described herein.

Examples

The following examples illustrate the disclosed apparatus and methods, but they are not intended to limit the scope of any claims thereto.

The queen bed illustrated in FIG. 3b and FIG. 4a was tested for its ability to cool a heated mattress, including a conventional mattress and a foam cell mattress as illustrated in FIG. 2. An electrical heating pad was used to heat the mattress for a fixed period (about 15 minutes), then the heating pad was removed, and then the mattress was allowed to cool with the fans operating to enhance cooling. The fans, which were operating in a mattress-side suction orientation (e.g., as illustrated in FIG. 5B), were effective at cooling the mattress and returning it to an ambient environmental temperature over a period of about 4 to 8 minutes.

Because other modifications and changes varied to fit particular operating requirements and environments will be apparent to those skilled in the art, the disclosure is not considered limited to the example chosen for purposes of illustration, and covers all changes and modifications which do not constitute departures from the true spirit and scope of this disclosure.

Accordingly, the foregoing description is given for clearness of understanding only, and no unnecessary limitations should be understood therefrom, as modifications within the scope of the disclosure may be apparent to those having ordinary skill in the art.

All patents, patent applications, government publications, government regulations, and literature references cited in this specification are hereby incorporated herein by reference in their entirety. In case of conflict, the present description, including definitions, will control.

Throughout the specification, where the compositions, processes, or apparatus are described as including components, steps, or materials, it is contemplated that the compositions, processes, or apparatus can also comprise, consist essentially of, or consist of, any combination of the recited components or materials, unless described otherwise. Component concentrations can be expressed in terms of weight concentrations, unless specifically indicated otherwise. Combinations of components are contemplated to include homogeneous and/or heterogeneous mixtures, as would be understood by a person of ordinary skill in the art in view of the foregoing disclosure.

PARTS LIST

10	mattress system (cooling or heating)	50
100	mattress deck or support	
110	deck support platform (sections 110A-D)	
120	fan or means for blowing/transporting air (fans 120A-D)	55
122	suction side of fan	
124	discharge side of fan	
130	air flow channel	
140	heating unit	
142	heated air	
150	cooling unit	
152	cooled air	
160	temperature sensor	
200	airflow spacer (thickness T in normal direction to support surface)	65
210	cover (mattress support cover)	

18

210A/210B	top/bottom surface of cover
230	airflow channel
300	mattress
305	containment frame
5	310 base
312	locator recess
314	locator pin
316	vent hole
318	open top area
320	sidewalls
330	endwalls
340	foam cells or foam springs
342	cylindrical channel
400	adjustable bed frame
410	frame support
420	support member
430	subframe
440	actuator
450	power supply
460	remote control
462	touch screen
464	remote control buttons (or other user input controls) for receiving user input
464A, 464B	first and second remote control buttons or other user input controls spaced apart (distance D; for activating and/or deactivating a child lock feature)

What is claimed is:

1. An assembly comprising:
an adjustable frame including an articulatable frame support and an actuator mounted to the articulatable frame support to adjust the position of the adjustable frame; a support platform connected to the frame support to articulate with the frame support, the support platform having a bottom surface facing the frame and a top surface facing opposite the bottom surface, the bottom surface having a peripheral edge;
a cover supported on the support platform and being flexible relative to the support platform; the cover covering the top surface of the support platform and extending downwardly from the top surface of the support platform and inwardly around the peripheral edge of the bottom surface of the support platform; the cover including an airflow spacer having a bottom surface facing the support platform and a top surface opposite the bottom surface of the airflow spacer, the cover designed to allow airflow therethrough with airflow entering the cover through the top surface of the airflow spacer and the bottom surface of the airflow spacer and exiting the cover through the top surface of the airflow spacer and the bottom surface of the airflow spacer; the cover being 1 mm-10 mm thick between the bottom surface of the airflow spacer and the top surface of the airflow spacer.

2. The assembly of claim 1, wherein the support platform is wood or metal.

3. The assembly of claim 1, wherein the adjustable frame includes a subframe supporting the frame support and the actuator, the frame support being moveable relative to the subframe by the actuator.

4. The assembly of claim 1, wherein the airflow spacer is a fabric mesh.

5. The assembly of claim 1, wherein the airflow spacer is a porous material.

6. The assembly of claim 1, wherein the airflow spacer is 2 mm-7 mm.

19

7. The assembly of claim 1, wherein the cover abuts the top surface of the support platform and the bottom surface of the support platform.

8. The assembly of claim 1, further comprising a mattress supported on and abutting the top surface of the airflow spacer.

9. The assembly of claim 1, wherein the assembly is free of fans mounted thereto.

10. The assembly of claim 1, wherein the support platform has a plurality of deck support sections connected to the articulatable frame support to articulate with the articulatable frame support.

11. The assembly of claim 10, further comprising at least one fan on more than one of the deck support structures, the fans being adapted to direct air from above a top surface of the deck support structures to below a bottom surface of the deck support structures and/or from below the bottom surface of the deck support structures to above the top surface of the deck support structures.

12. The assembly of claim 11, wherein the fans are mounted to the bottom surfaces of the deck support structures.

13. The assembly of claim 1, further comprising at least one fan on the support platform, the fan being adapted to direct air from above the top surface of the support platform to below the bottom surface of the support platform and/or from below the bottom surface of the support platform to above the top surface of the support platform.

14. An assembly comprising:

a frame;

a support platform supported by the frame, the support platform having a bottom surface facing the frame and a top surface facing opposite the bottom surface, the bottom surface having a peripheral edge; a cover supported on the support platform and being flexible relative to the support platform;

20

the cover covering the top surface of the support platform and extending downwardly from the top surface of the support platform and inwardly around the peripheral edge of the bottom surface of the support platform; the cover including an airflow spacer having a bottom surface facing the support platform and a top surface opposite the bottom surface of the airflow spacer, the cover designed to allow airflow therethrough with airflow entering the cover through the top surface of the airflow spacer and the bottom surface of the airflow spacer and exiting the cover through the top surface of the airflow spacer and the bottom surface of the airflow spacer;

the cover being 1 mm-10 mm thick between the bottom surface of the airflow spacer and the top surface of the airflow spacer.

15. The assembly of claim 14, wherein the support platform is wood or metal.

16. The assembly of claim 14, wherein the cover abuts the top surface of the support platform and the bottom surface of the support platform.

17. The assembly of claim 14, further comprising a mattress supported on and abutting the top surface of the airflow spacer.

18. The assembly of claim 14, wherein the assembly is free of fans mounted thereto.

19. The assembly of claim 14, further comprising at least one fan on the support platform, the fan being adapted to direct air from above the top surface of the support platform to below the bottom surface of the support platform and/or from below the bottom surface of the support platform to above the top surface of the support platform.

20. The assembly of claim 19, wherein the fan is mounted to the bottom surface of the support platform.
